DESIGN FOR A WEIGHING SCALE

Leonard Maguire, St. Johnsbury, Vt., assignor to
Fairbanks, Morse & Co., Chicago, Ill., a cor-
poration of Illinois

Application December 28, 1946, Serial No. 135,825

Term of patent 14 years

(Cl. D52—10)

To all whom it may concern:

Be it known that I, Leonard Maguire, a citizen of the United States, residing in the town of St. Johnsbury, county of Caledonia, State of Vermont, have invented a new, original, and ornamental Design for a Weighing Scale, of which the following is a specification, reference being had to the accompanying drawing, forming a part thereof.

In the drawing:

Fig. 1 is a top plan view of a weighing scale, showing my new design;

Fig. 2 is a front elevational view thereof, and
Fig. 3 is a side elevational view thereof.

I claim:

The ornamental design for a weighing scale, substantially as shown.

LEONARD MAGUIRE.
